United States Patent Office

Des. 176,634
Patented Jan. 10, 1956

176,634

ICED FOOD SERVER

Peter Schlumbohm, New York, N. Y.

Application January 11, 1954, Serial No. 28,477

Term of patent 14 years

(Cl. D44—15)

FIG.1.

FIG.2.

FIG.3.

Fig. 1 is an elevational view of an iced food server, showing my new design;

Fig. 2 is a top plan view thereof; and

Fig. 3 is a perspective view of the food holding portion thereof.

I claim:

The ornamental design for an iced food server, as shown.
